Ralph A. Shepard. By his Attorneys,

John Garbers Inventor

UNITED STATES PATENT OFFICE.

JOHN GARBERS, OF CHAPMAN, NEBRASKA.

MAIL-BAG CATCHER.

SPECIFICATION forming part of Letters Patent No. 634,131, dated October 3, 1899.

Application filed July 8, 1899. Serial No. 723,217. (No model.)

To all whom it may concern:

Be it known that I, JOHN GARBERS, a citizen of the United States, residing at Chapman, in the county of Merrick and State of Nebraska, have invented a new and useful Mail-Bag Catcher, of which the following is a specification.

This invention relates to apparatus for receiving and delivering mail-bags from the postal car of a moving train, and has for its object to secure a positive and certain delivery and reception of the mail-bags with the least possible wear and tear upon the latter and with the greatest despatch and convenience to the clerks and at the same time to obviate projecting arms when the apparatus is not in use.

To these ends the present invention consists in the combination and arrangement of parts, as will be hereinafter more fully described, shown in the accompanying drawings, and particularly pointed out in the appended claim, it being understood that changes in the form, proportion, size, and the minor details of construction may be made within the scope of the appended claim without departing from the spirit or sacrificing any of the advantages of the present invention.

In the drawings, Figure 1 is a perspective view showing the catcher in the act of receiving and delivering a mail-bag to the crane. Fig. 2 is a rear elevation thereof immediately after the catcher has passed the crane. Fig. 3 is a top plan view of the delivery end of the catcher. Fig. 4 is a detail elevation of the standard and the lower arm of the crane, showing the hinged connection therebetween.

Corresponding parts in the several figures of the drawings are designated by like characters of reference.

Referring to the accompanying drawings, 1 designates the standard of the mail-crane, which is arranged alongside of the railroad-track and carries the apparatus for supporting the mail-bag which is to be transferred to the postal car of a moving train. Pivoted intermediate of its ends and to the upper end of the standard is a supporting-arm 2, provided at its outer free end adjacent to the railroad-track with a cross-head 3, which is bowed downwardly in opposite directions from the

arm and has its opposite ends bent upward, so as to provide seats 4 for supporting the mail-bag which is to be transferred to the postal car. 55 The opposite end of this supporting-arm is provided with a pendent coiled spring 5, which is connected at its lower end to the rear side of the standard, so as to throw the outer end of the arm upward and out of the way after the 60 mail-bag has been transferred to the postal car, as shown in Fig. 2. The lower receiving-arm 6 is connected to the front face of the standard 1 by means of a suitable hinge 7, so that said arm may be folded downward along- 65 side of the standard after receiving the mail-bag from the postal car. At the outer free end of this latter arm there is provided a cross-head 8, which is arranged reversely to the upper cross-head 3, being bowed upwardly 70 at opposite sides of the arm and having its outer extremities bent downwardly, so as to provide seats 9 for holding said arm in its elevated position to receive a mail-bag from the postal car. 75

To set the apparatus for delivering a mail-bag to a postal car while in motion, the arms 2 and 6 are brought into horizontal position and a mail-bag 10 is suspended therefrom by means of a large ring 11, which is connected 80 to the middle of the bag in any desired manner and embraces the seats 4 at the respective ends of the cross-heads 3 and 8, it being understood that the bag is located upon that side of the frame on which the train is moving. Thus it will be seen that the bag is suspended from the upper cross-head 3 and embraces the lower cross-head 8, so that the two supporting-arms 2 and 6 are held in a substantially horizontal position in readiness to 85 deliver and receive the mail-bags.

The means for transferring the mail-bag from the crane to the postal-car comprises a catcher-arm 12, which is located substantially parallel to the car and is connected therewith 95 by means of a transverse rod or bar 13, projecting laterally outward from the car 14. The connecting-bar is carried at its inner end by means of a longitudinally-disposed supporting-bar 15, having its opposite ends journaled 100 at the opposite sides of the car-door and provided with an operating-handle 16, whereby the catcher-rod 12 may be swung into the door-way after receiving the mail-bag or when not

in use. The rear end of the catcher-rod 12 is provided with rearwardly-extending spring-jaws 17, having their outer free extremities bowed inwardly, as at 18, so as to form seats 5 for supporting the mail-bag to be delivered to the crane. As clearly indicated in Fig. 1, the mail-bag 19, which is to be delivered to the crane, is also provided with a large ring 20, as described for the former mail-bag, and 10 this ring embraces the seats of the spring-jaws 17, whereby the mail-bag is suspended from the rear end of the catcher-arm.

In the operation of the device, as clearly shown in Fig. 1, it will be seen that the connecting-arm 13 is of a length to dispose the catcher-arm 12 intermediate of the cross-heads 3 and 8, so that said arm is adapted to be received within the ring 11, whereby the mail-bag 10 will be removed from the cross-heads when the connecting-bar 13 strikes the ring 11, and the latter will remain upon the arm. The ring 20 of the mail-bag to be transferred to the crane receives the adjacent end of the lower cross-head 8 and is removed from 25 the spring-jaws 13 by contact with the adjacent side of the lower arm 6 of the crane and remains upon the cross-head. Immediately upon the ring 11 being removed from the cross-heads the spring 5 will throw the outer free 30 end of the upper arm 2 upwardly and the lower arm 6 will simultaneously drop downwardly, so that neither of the arms projects outwardly from the standard when the crane is not in use. It will of course be understood 35 that the relative disposition of the bag 19 from the supporting-rod 13 is such that the ring 11

is not removed from the cross-heads until said bag has been engaged with the lower cross-head, so that a safe and positive transfer of the bag is insured.

From the foregoing description it will be apparent that the present apparatus provides an exceedingly simple and durable mail-bag catcher, the parts being few in number and positively connected together. Furthermore, 45 there are no spring-catches to become worn and broken or impaired by the effects of the weather, and the arms of the crane are effectively maintained out of the way when not in use.

What I claim is—

In an apparatus of the class described, the combination with a crane having upper and lower arms provided at their outer free ends with cross-heads, of a mail-bag ring embracing 55 respective ends of the cross-heads, a mail-bag catcher-arm, a supporting-rod carried by a postal car and spacing the catcher-arm outward from the car, opposite rearwardly-extending spring-jaws connected to the rear end 60 of the catcher-arm, and having their rear free extremities bowed inwardly and forming seats, and a mail-bag ring embracing the seats of the springs, substantially as and for the purpose set forth.

In testimony that I claim the foregoing as my own I have hereto affixed my signature in the presence of two witnesses.

JOHN GARBERS.
